UNITED STATES PATENT OFFICE.

MALCOLM A. SCHWEIKER, OF LANSDALE, PENNSYLVANIA, AND JAMES R. WESTBROOK, OF METUCHEN, NEW JERSEY.

TOOL AND MACHINE FOR FETTLING FLOOR AND WALL TILE.

Original application filed April 16, 1923, Serial No. 632,590. Divided and this application filed July 21, 1924. Serial No. 727,335.

This invention relates to fettling tools and to machines for fettling floor and wall tile.

"Fettling" is the operation of beveling, or chamfering the edges of a floor or wall tile 5 after the latter comes from the tile press, the purpose being to remove the fin-like projections from the tile and to suitably chamfer or bevel the edges of the upper face of the tile.

10 In tile presses there is a certain clearance between the plunger and the die casing and as the pulverized clay which is used for the production of the tile contains approximately 8% to 12% moisture, the clearance 15 results in the formation of rough edges or fin-like projections. These are fettled by hand labor, the workers usually being girls or women who sand paper the projections from the tile and form the chamfer on the 20 upper edges thereof. Hand fettling results in lack of uniformity of the edges of the tile and size of the chamfer, beside which there is a tendency to carelessly brush the tile and to allow minute particles of clay to remain 25 upon it. Hand fettling also adds considerably to the expense of production.

Much tile is ruined by workers before they become proficient fettlers and the proficient fettlers often produce imperfectly fettled 30 tile.

The fettling operation is considered to be necessary for the purpose of giving the tile a better appearance when it is completed, and, also, the chamfer stops the "glaze" 35 from running over the edge of the tile and forming beads, roughnesses, or small lumps, if the tile is to be subsequently glazed. Roughnesses, beads, or small lumps of glaze 40 inconvenience the tile-setter in the rapid setting of tile and detract from the appearance of the tile.

Our machine has fettling tools herein-after described and shown in the drawings, constructed and arranged for the purpose 45 of fettling two tiles at a time as they are delivered from a tile press which forms two tiles simultaneously.

We wish it understood, however, that some tile presses make only one tile at a 50 time, while others make as many as four, but in the tile industry as more tile presses forming two tiles at a time are used than

those forming a lesser or greater number, we have described and illustrated our machine and the fettling tools as constructed and arranged for the treatment of tiles delivered in pairs, in succession, to the machine. It is to be understood, however, that the invention is not limited to the duplex construction we have disclosed and we claim 55 the fettling tools and other mountings, as well as combinations in which they are involved, whether the tools be used singly or in pairs.

Our novel fettling tools possess a spring 60 action so that they automatically adjust themselves to varying thicknesses of tile or to tiles of varying degrees of hardness. This adaptability insures uniformity of fettling under widely varying conditions. Furthermore, the fettling tools are constructed to 65 resist the very considerable wear offered by the abrasive nature of clay bodies.

Our improved fettling tools are mounted 70 in a novel manner for adjustment to meet 75 any conditions encountered in this class of work.

We are aware that modifications may be resorted to in certain particulars without departing from the essential principles of 80 the invention and we do not restrict the invention to the specific embodiments herein-after described and shown in the drawings, except where specifically set forth in the 85 claims.

This application is a division of Serial No. 632,590, filed April 16, 1923, which became Patent No. 1,536,411, May 5, 1925.

In the accompanying drawings:

Fig. 1 is a detail perspective view of 90 the left hand end of the machine set forth in our aforesaid patent, showing the mounting and action of our fettling tools.

Fig. 2 is a detail perspective view, broken away, of the operative end of one form of 95 a fettling, scraping, or cutting tool made according to our invention.

Fig. 3 is a detail side elevation, partly broken away, of another form thereof.

Fig. 4 is an end elevation of the tool of 100 Fig. 3.

Fig. 5 is a detail perspective of one of the bridges, supports, or carriers for the fettling, cutting, or scraping tools; and

Fig. 6 is a similar view of a part of the cross piece or support for the guides for the tile guiding belts of the machine.

Only so much of the machine of our afore-
5 said patent is shown as will afford a clear
understanding of the manner in which the
present invention is used.

That end of the machine which receives
10 the tiles from the tile press is shown in
Fig. 1. A part of the machine frame ap-
pears at 7, a roller 12 being suitably car-
ried thereby. The conveyor belts 11 pass
over said roller and over other rollers and
pulleys, not shown.

15 Brushes 3 carried by a frame 6 pivoted
at 8 to main frame 7 and adjustably sus-
pended at 9, 10, clean the bottom of the
tiles as they are pushed from the tile press
onto the upper stretches of the belts 11,
20 which latter travel in the direction shown by
the arrows.

A tapered parting strip or divider 1 is
employed to guide the two streams of tiles
coming from the press and keep them in
25 position to advance longitudinally of them-
selves when they enter the machine as tiles
sometimes have a tendency to turn cross-
wise, or partially so, as they are pushed
from the press.

30 It is of great importance that the tiles be
kept in perfect alinement, that is, travel
along a predetermined path while being
fettled. To that end, we have provided
novel means for causing the tile to travel
35 in a straight path while its longitudinal
edges are fettled and, after the tile has been
turned crosswise of itself to travel in a
straight path while its transverse edges are
undergoing fettling.

40 The means for turning the tile is not
herein shown, nor do we disclose herein the
set of fettling tools which acts on the trans-
verse edges of the tile but full disclosure
is given in aforesaid patent.

45 The necessity for keeping the tiles in
alinement arises from the fact that if a tile
turns or gets out of alinement, irregular
fettling will result and the tile will be
damaged.

50 The means for guiding the tiles so that
they will travel in straight paths, in suc-
cession, one after another, while being fettled,
comprises belts of small size which are pref-
erably round in cross sectional shape, these
55 belts being arranged to engage the sides or
edges of the tiles with a certain degree of
tension, as shown in Fig. 1. This tension
is conveniently effected by the use of rollers
or sheaves which bear on the belts.

60 As illustrated, the alinement belts 34 are
round or cylindrical and are endless. Like
the belts 11 the belts 34 pass around the
roller 12 and other rollers and drums not
shown.

Certain of the tension means employed
for holding the stretches of alinement belts
34 with any desired tension against the
sides of the tile whose longitudinal edges
are being fettled, comprise brackets 39 and
adjustably mounted sheaves 40.

The innermost alinement belts 34 are
held at the proper height and suitably oper-
ated alongside the parting strip 1 by pass-
ing around a sheave or pulley 14 integral
with the roller 12. The outermost aline-
ment belts 34 pass around the outsides of
the belts 11 and their under stretches travel
through adjustable guide eyes 37 carried by
cross pieces 38 secured to the frame 7, see
Fig. 6. The guide eyes 37 may be adjusted
transversely of the machine to afford the
requisite spacing between the belts 34 and
they may also be adjusted vertically to pro-
vide any desired tension on the left hand
stretches of the alinement belts 34.

85 The tiles are shown at T.

At the entry end of the machine, as shown
in Fig. 1, the alinement belts 34 diverge so
that if the tile is received in other than
aligned position, it is gradually brought to
proper alinement. The adjustability and
position of the guides 37 enable the outer
alinement belts 34 to be arranged as de-
sired.

90 Fettling of the longitudinal edges of the
tiles T is accomplished as shown in Fig.
1 by the use of improved fettling tools and
mountings.

Bridges 41, Figs. 1, 5, which are secured
to the sides of the frame at 42 and overlie
100 the belts 11 and 34, carry the fettling tools.
The ends of the bridges 41 are provided
with slots 43, Fig. 5, to receive the fasten-
ing screws 42, by which any desired adjust-
ment of the bridges 41 may be obtained to
properly position the general extent of the
fettling devices. The fettling devices or
tools have shanks 44 of springy material
which are connected to the bridges 41 by
adjustable screw fastenings 45 which are
110 preferably bolts with wing nuts, the shanks
of the bolts passing through slots 43 in the
bridge 41. This mounting provides for
bodily transverse adjustment of the fettling
tools and, also, for swinging them pivotally
115 where the fastenings 45 pass through them.

120 For the purpose of swinging the shanks
44, they are connected to the sides of the
frame by rods 47 which have screw-threaded
ends carrying wing nuts 48. Thus, after
bodily adjustment of a given shank 44, it
may be swung on its pivot and set pre-
cisely as desired to accomplish the fettling
operation and, thereafter, any further ad-
justment may be had according to condi-
tions to be met.

125 The shanks 44 are preferably formed of
brass for the reason that they may be easily

bent to the peculiar shape illustrated in Fig. 1 and require no special tools for bending. It is to be noted that the operation of fettling is for the purpose of chamfering or beveling the edges of the tile bounding the outer or upper face thereof. In Fig. 1 the tiles T are being drawn forward by the belts 11 while held in alinement by the belts 34 and the fettling tools have begun the fettling 10 operation by forming the chamfers or bevels B. As the tiles advance, the bevels or chamfers B are formed until the tile is fettled on both of its longitudinal edges from end to end. The tile then passes on and is turned 15 through an angle of 90° for fettling its transverse edges, as set forth in our aforesaid patent.

Clay being of an abrasive nature, we have found that spring steel is best adapted for 20 service as the cutting tool which engages the edge of the tile T and forms the bevel or chamfer thereon. In Fig. 2 there is shown one form of shank 44 for holding the fettling or cutting tool 49. In this form 25 the brass shank 44 is slashed and the metal struck up in the form of a friction loop 50 which frictionally holds the steel tool 49 whose end abuts the lip 51 on shank 44.

The form of tool and holding means 30 shown in Fig. 1 and other figures of the drawings is that appearing in Figs. 3 and 4. The brass shank 44 has the same lip 51 shown in Fig. 2 but in lieu of the friction loop 50 there is provided a U-clamp 52 which straddles the shank 44 and the cutting tool 49 and screws 53 clamp the tool 49 to the shank 44. This form of tool holder 35 securely connects the steel fettling tool 49 against any possibility of slippage.

40 In either form of tool holder set forth, as the cutting tool 49 becomes worn, it can be moved forwardly against the lip 51 and a new tool substituted whenever desirable or necessary.

45 It will be understood that the features of adjustment provided for the brackets and sheaves that bear on the alinement belts 34, and the arrangement and adjustability of the fettling tools, permit the machine to be 50 arranged to fettle tiles of different dimensions.

We claim:

1. In a machine for fettling floor and wall tiles, the combination with a carrier belt for supporting and advancing the tiles, of a 55 bridge arranged in crosswise relation to, and located above, said belt, and tile fettling means carried by said bridge adapted to chamfer an edge of the tiles.

2. In a machine for fettling floor and wall 60 tiles, the combination with a carrier belt for supporting and advancing the tiles, of a bridge arranged in crosswise relation to, and located above, said belt, and independent tile fettling tools having shanks independently 65 adjustably mounted on said bridge so that the tools may be independently set to simultaneously fettle opposite edges of the tiles as desired.

3. In a machine for fettling floor and wall 70 tiles, the combination with a tile carrier for advancing the tiles, of side frames, a bridge connecting the side frames and located above the tile carrier, and adjustable tile 75 fettling tools having shanks independently adjustably mounted on the bridge, and independent adjustable rods connecting the respective shanks with the side frames, whereby the different tools may be independently 80 adjusted.

4. A fettling tool for a floor and wall tile fettling machine comprising a shank having a lip or abutment, an independent cutting tool adapted to engage the lip or abutment, and a clamping device connecting the tool 85 and shank which permits adjustment of the cutting tool in the general direction of the length of the shank, and removal of the said tool from the shank.

5. In a machine for fettling floor and wall 90 tile, a fettling tool having an inherently springy shank.

6. In a machine for fettling floor and wall tile, a fettling tool having a spring-operated shank.

7. In a machine for fettling floor and wall tile, a spring-operated fettling tool.

In testimony whereof we affix our signatures.

MALCOLM A. SCHWEIKER.
JAMES R. WESTBROOK.
